A. W. KNUTSON.

SCOOP GATE,

APPLICATION FILED JAN. 25, 1918.

1,326,274.

Patented Dec. 30, 1919.

UNITED STATES PATENT OFFICE.

ALFRED W. KNUTSON, OF GALESBURG, ILLINOIS, ASSIGNOR TO GEORGE G. BAYNE, OF BUSHNELL, ILLINOIS.

SCOOP-GATE.

1,326,274.

Specification of Letters Patent. Patented Dec. 30, 1919.

Application filed January 25, 1918. Serial No. 213,726.

To all whom it may concern:

Be it known that I, ALFRED W. KNUTSON, a citizen of the United States, and resident of Galesburg, in the county of Knox and State of Illinois, have invented a new and useful Scoop-Gate, of which the following is a specification.

My invention relates to tail-boards for farm-wagons, of that type wherein the features of a closure and a shoveling board are provided. Wagons equipped with tail-boards of this character are frequently used for carrying grain and for dumping it at the elevator. It is essential therefore that the scoop-gate be close fitting, in order that no grain may be lost in local transporting; that it be readily operable against the resistance of the confined load; that it be capable of being held open at the preferred distance to allow proper discharge from the tilted wagon-body; that the last recited means—the holding elements—be quickly operable, in order to instantly stop or to regulate the flow of grain, that the gate have absolute freedom of movement; that when opened to the shoveling-board position it will not permit grain to dribble, and that it be capable of being changed from one position to another with facility. To incorporate in a scoop-gate all the foregoing recited features is one of the objects of the invention.

Wagons of the type referred to are used also for hauling hogs, sheep and other small animals to market. To provide for such wagons a scoop-gate which is provided with novel means whereon the valve-board may be tilted (or swung in vertical planes,) slid back and forth, and be supported at such height that the animals may freely pass thereunder, constitutes another object of the invention.

To dispense absolutely with any guide or the like which is liable to cause the gate to bind as it is moved therethrough and which therefore is the cause of an imperfect operation, is a particular object.

Minor objects will presently appear. Some of these will be obvious and others particularly pointed out.

In the accompanying drawings, which illustrate a preferred embodiment of my invention:

Figure 1 is a rear elevation of my im-

proved scoop-gate in position on a wagon-box;

Fig. 2, a reversed view of the same, a front elevation, the wagon-box-bottom shown in section;

Fig. 3, a substantially central longitudinal section illustrating some of the ordinary positions in which it is possible to place and operate the scoop-gate;

Fig. 4, an enlarged perspective detail showing particularly the construction of the shelf on which the movable gate-board may be tilted, moved back and forth, and supported; and

Fig. 5, an enlarged detail showing particularly the means for sustaining the movable gate-board in load-dumping position.

Considering the drawings in detail, 2 denotes the bottom; 3, 3 the sides; and 4 the rear cross-strip of a common type of wagon-body.

5 denotes what may be termed the stationary frame inasmuch as it is adapted to be moved from its normal position only when the scoop-gate is used as a shoveling-board. It comprises wings 6, 6', standards 7, 7', and cross-pieces 8, 8', suitably secured together. This frame, which is old in the art, has the usual placement, the standards resting on the box-bottom 2 and the wings embracing the sides of the box.

9, 9' indicate a pair of shelves each of which is preferably in the form of a plate secured by bolts or rivets 9" to one of the standards and having a projection extending toward the longitudinal central line of the scoop-gate and affording a valve-supporting shoulder 10. 11 denotes a centrally arranged movable gate-board which for the purposes of this specification shall herein-after be termed the valve, inasmuch as its functions are to prevent or to allow and to regulate the flow of grain and to permit or prevent the admission or the exit of animals to and from the wagon-body. It is preferably made up of several boards united near their upper and lower portions by angle irons 12 and 13 respectively, the horizontal branches of these irons resting normally upon the bars 8 and 9 respectively. 14 denotes an operating handle. It will be noted that the valve 11 may slide freely vertically between the opposed edges of the standards 7, 7'; that it may be swung on the

shoulders 10 which act as fulcrums therefor; and that when it is moved to the horizontal position shown in Fig. 4 it will be self-supported, for it has been moved forward past its horizontal central line whereby its forward end is tending to fall by gravity, but this falling movement is prevented by the cross-bar 8. This is the position in which the valve is placed when loading or unloading animals, lumber and other things which enter or are taken from the rear end of the wagon-body, and is illustrated clearly in Fig. 4.

15 indicates the strap portion of a bolt 15' 15 by which the cross-bars 8 and 8' are secured to the adjacent wings.

Mounted in eyes in hinge-brackets 16 secured by bolts 17 to the bar 8 is a pin 18 on which is hinged the eye of a valve supporting and locking arm 19 the free end of which rests normally on top of the valve 11, to thereby lock it in closed position as shown best by full lines in Fig. 1 and dotted lines in Fig. 5. When the wagon-box is 25 tilted to dump its load, or at any other time when it is desired to hold the valve partly open, said free end is brought into position to rest beneath the angle-iron 12 on the rear face of the valve, see Fig. 5. This adjustment and lock is illustrated also by dotted lines in Fig. 3, wherein are additionally shown, by dotted lines *a* and *b*, other positions in which the valve may be placed and held by the operator.

35 When it is desired to use the scoop-gate as a shoveling-board the lower edge of the valve 11 is first let fall in front of the cross-bar 8' which restrains it from rearward movement, the terminals of the angle-iron 40 13 overlapping their adjacent standards 7 and 7' and preventing its rearward movement. The upper portion of the valve is held in like manner by the cross-bar 8 and angle-iron 12, and the valve is supported 45 by the floor 2. The valve is thus secured firmly to and in the frame 5. To each side of the wagon-box is secured a strap-bolt 21 having an eye which engages the eye of a supporting-link 22 which passes 50 through eyes in plates 23 secured each on one of the standards, and through registering eyes in said standards, each link bent at its lower end to form an enlargement of such size that it will not enter the eyes in 55 said standards and plates. The operation of these is clearly shown by dotted lines in Fig. 3. When it is desired to replace the shoveling-board in its normal position the links 22 are brought beneath spring-clips 60 24 in order to prevent them from swinging.

I wish to call particular attention to the fact that the shoulder 10 constitutes a free support with which the valve 11 is in no manner connected or attached; that the

valve will move on it or over it without any 65 danger of binding; and that the valve may be moved backward and forward while entirely out of contact with it. It being kept in mind that wood (such as the valve) "swells" in moist weather, and that metallic 70 guides must fit reasonably close and are easily bent,—in either of which events there is liability to inferior operation or even inoperation—the advantage of a support of the type or nature of the shoulders 10 will 75 be evident, as will also the fact that any similarly operating elements, projecting toward each other from the opposed edges of the standards 7, 7', might be substituted therefor.

Having thus described the nature of the invention I claim as new the following, to-wit:

1. In a device of the character described, a frame including spaced standards, a valve 85 normally closing the space between them, a stop on the valve, and a hooked hinged arm adapted to engage alternatively with the top of the valve and with said stop to hold the valve in closed and inclined positions respectively.

2. In a device of the character described, a frame including spaced standards, a valve normally closing the space between them, means whereon the valve may tilt about a 95 point intermediate its upper and lower edges and slide, and a hinged arm for holding the valve inclined relatively to the frame.

3. In a device of the character described, 100 a frame including spaced standards and a cross-bar connecting them, a valve normally closing the space between the standards, means whereon the valve may be tilted about a point intermediate its upper and lower 105 edges, and means hingedly connected with the cross-bar and adapted to hold the valve in both closed and tilted position.

4. In a device of the character described, a frame including spaced standards, a valve 110 normally closing the space between the standards, means whereon the valve may be tilted about a point intermediate its upper and lower edges, a stop on the valve, and means having thrust engagement with said 115 stop and thereby holding the valve in tilted position.

5. In a device of the character described, a frame including spaced standards, and a cross-bar connecting them, a valve normally 120 closing the space between the standards, means whereon the valve may be tilted, a stop on the valve, and an arm hingedly connected with the cross-bar and adapted to engage said stop to hold the valve in inclined position.

In witness whereof I hereto sign my name.
ALFRED W. KNUTSON.
